LOCK

Jacob Pauloski, Jane Pauloski, and Jean Pauloski,
Wooster, Ohio

Application June 1, 1937, Serial No. 145,852

1 Claim. (Cl. 70—284)

The invention relates to a lock and more especially to key operated combination locks. The primary object of the invention is the provision of a lock of this character, wherein 5 through the use of a dial and an indicator carried by the key of the lock the turning barrel, which is locked within the cylinder, can be freed by the setting through the use of the key under a definite combination identified between said dial and indicator so that the locking bolt of the lock may be thrown from a locked position to release a door or other part locked and thus it will be impossible to release the bolt except by the setting of the combination in the use of the proper key for the lock.

Another object of the invention is the provision of a lock of this character, wherein the locking bolt, which is thrown to locking position by a spring, can be released by the key of the lock without first operating the combination which has been normally operated to free the barrel for the turning thereof by the key similarly to the ordinary tumbler controlled barrel lock.

A further object of the invention is the provision of a lock of this character, wherein the barrel of the same accommodates tumblers which are key controlled for locking the barrel to the cylinder while supplementing these tumblers is a combination mechanism which also releasably locks the barrel to the cylinder, therefore, in one instance the latching bolt of the lock can be released on releasing the tumblers from the cylinder and in another instance it requires the working of the combination mechanism in addition to the tumblers for the release of the bolts so that the lock is of a dual operative kind, namely, a key operated lock for the release of the bolt or a combination key operated lock for the release of the bolt or these cooperating together for the release of the bolt.

A further object of the invention is the provision of a lock of this character, wherein both the tumbler mechanism and the combination mechanism are confined within a barrel, the combination mechanism being actuated through a plurality of locking rings while the tumbler mechanism is operated by a key, being required that the tumbler mechanism be first operated before the combination mechanism can be operated and thus for the successful working of the lock, it is necessary that a person have knowledge of the particular combination set of the lock for the working thereof as well as the possessor of the required key for the lock.

A still further object of the invention is the

provision of a lock of this character, which is comparatively simple in its construction, thoroughly reliable and efficient in operation, readily applied to doors or other parts to be locked, strong, durable, and inexpensive to manufacture.

With these and other objects in view, the invention consists in the features of construction, combination and arrangement of parts as will be hereinafter more fully described, illustrated in the accompanying drawings, which disclose the preferred embodiment of the invention and pointed out in the claim hereunto appended.

In the accompanying drawings:

Figure 1 is an elevation of the lock constructed in accordance with the invention showing the key therefor inserted for the operation of the lock.

Figure 2 is an enlarged plan view partly in section of the lock, the key being inserted in the lock.

Figure 3 is a vertical sectional view through the lock showing the cylinder and other adjuncts in elevation.

Figure 4 is an enlarged vertical longitudinal sectional view through the lock.

Figure 5 is a sectional view on the line 5—5 of Figure 4 looking in the direction of the arrows.

Figure 6 is a sectional view on the line 6—6 of Figure 4 looking in the direction of the arrows.

Figure 7 is a sectional view on the line 7—7 of Figure 4 looking in the direction of the arrows.

Figure 8 is a sectional view on the line 8—8 of Figure 4 looking in the direction of the arrows.

Figure 9 is a sectional view on the line 9—9 of Figure 4 looking in the direction of the arrows.

Similar reference characters indicate corresponding parts throughout the several views in the drawings.

Referring to the drawings in detail, A designates generally a portion of a swinging door while B diagrammatically discloses a portion of the frame for the door. At the inner side of the door A is a latch casing 10 being of conventional type having a spring thrown latching or locking bolt 11 engageable with a keeper 12 on the door frame. Formed transversely in the door A at the proper location with respect to the latched casing 10 is a hole or opening 13 accommodating a combination lock which comprises a stationary cylinder 14 in which is fitted a turning barrel 15. This cylinder has formed therewith at the outer side of the door A a circular dial 16 provided with exposed numerals ranging from one to twelve in a circular course and in association

with degree marks 17 effecting a combination scale. The cylinder 14 at the inner side of the dial 16 is suitably notched at 18 for accommodating cleats 19 engaged by fasteners 20 and these cleats secure the cylinder 14 in place and hold the same stationary while the dial overhangs a concavo-convexed facing collar 21 which encircles the cylinder 14 for service as a frontal fitting to the door A about the cylinder, the cleats 19 being concealed by the said collar 21 when in place.

The turning barrel 15 as is usual is formed with a central longitudinally disposed key slot or way 22 for a tumbler releasing key 23. The tumblers 24 within the barrel 15 each is thrown by a spring 25 to locking position with the cylinder 14 in diametrically opposed slots 26 in said cylinder and in this manner the barrel 15 is locked against turning movement in the cylinder 14, the turning movement of the said barrel 15 being effected by the key 23 when inserted in the way 22 for the release of the tumblers 24 in said barrel from the cylinder 14.

The key 23 in this instance has a circular head 27 or finger grip 27 to which is pivoted eccentrically thereto a swinging pointer or indicator arm 28 which when swung away from the head toward the dial 16 will coat with the numerals exposed by said dial and the degree marks 17 for a combination setting of the lock in the latching and unlatching of the bolt 11 with and from the keeper 12.

Formed with the barrel 15 centrally thereof at its inner end is a journal arbor or spindle 29 which has engaged therein a cross or transversely disposed fastener 30 for a cam ring 31 encircling the arbor or spindle 29 for the fixing of this ring thereto while encircling the said arbor or spindle 29 at opposite sides of the ring 31 are the combination rings 32 and 33, respectively, these at their sides next to the ring 31 being formed with mutilated or broken annular grooves or channels 34, one being of greater extent than the other and received therein is an actuator pin 35 fixed in the ring 31 concentrically thereof. The rings 32 and 33 are free of the arbor or spindle 29 of the barrel 15 and are frictionally held through the medium of loop springs 36 interposed between the said ring 31 and the rings 32 and 33, respectively, and in this manner such springs 36 will effect a braking action on the rings 32 and 33 to avoid the rotating of the same on the rotation of the barrel 15 and its arbor or spindle 29. These rings 31, 32, and 33 when concentrically of the arbor or spindle 29 are snugly fitted within the cylinder 14 and the said rings 32 and 33 are formed with notches 37 adapted for register with a receded cam notch 38 in the ring 31 which notch 38 provides a cam surface 39 on the said ring 31 for a purpose presently described.

Accommodated in the inner open end 40 of the cylinder 14 is a turn table 41 formed with a guide way 42 transversely thereof at its inner face 43 for accommodating a radially shiftable locking slide 43 having a locking finger 44 movable into and out of the notches 37 and 38, respectively, of the rings 31, 32, and 33 when these notches 37 and 38 are in register with each other and such finger when moved outwardly of the said notches through the action of the cam face 39 thereon is accommodated within a keeper slot 45 formed longitudinally in the cylinder 14 at one side thereof. The locking slide 43 is acted upon by a spring 46 which urges the finger 44 into the notches 37

and 38 when registering with each other and said finger when engaged in these notches locks the rings 32 and 33 with the arbor or spindle 29 of the barrel 15 so that said barrel can be rotated in the cylinder 14 when the key 23 has released the tumblers 24 within the barrel from said cylinder.

The turn table 41 is held within the cylinder 14 by a loop spring 47 which latter is engaged with the said cylinder and holds this turn table frictionally assembled with a bridge piece 48 pinned at 49 to the said table. This bridge piece 48 has a central swiveled lug 50 engaged in the arbor or spindle 29 so that the barrel 15 will be centered in the cylinder 14 and swiveled there-with.

The turn table has centrally thereof at its outer side a tubular hub 51 having loosely fitted therein a partially rotatable coupling plug 52 in which is pivoted at 53 a turning key bar 54 which is engaged in a throw eccentric 55 for the latch bolt 11 in the casing 10. This plug 52 is fitted within the hub 51 for partial rotation therein by set screws 56 mounted in said hub and projecting into a mutilated annular groove 57 provided peripherally in the said plug 52. In this manner the plug can turn independently of the hub 51 for a limited distance and when at the limit of movement the set screws 56 operate to have the plug 52 turn with the turn table 41. This limited independent movement of the plug 52 within the hub 51 permits of the release of the latch bolt 11 through a hand turn knob 58 fitted with the casing 10 and also the latching of the bolt through spring action interiorly of said casing as is usual.

The rings 32 and 33 with the notches 37 therein are set through the extent of the channels or grooves 34 in cooperation with the pin 35 in accordance with a certain determined combination identified by the numerals ranging from one to twelve on the dial 16 and the degree markings 17 thereon. When the barrel 15 has been unlocked from the cylinder 14 by the key 23 acting upon the tumblers 24 and turned to an extent both clockwise and counter-clockwise by the key 23 in the way 22 in conformity to the location of the numerals one to twelve and the degree marks 17 selected for a particular combination operation of the lock thereunder throws the latch bolt 11 and the unlocking of the door or other part A is had. Under this selected combination of the lock, it is, of course, understood that normally the finger 44 is engaged in the slot 45 in the cylinder 14 and thus the turn table 41 is held fixed against turning action so that the latching bolt 11 can not be thrown to a released position. This throwing of the latch bolt 11 requires the turning of the barrel 15 to bring the rings 31, 32, and 33 into a position that the notches 37 and 38 therein will be in register with each other whereupon the finger 44 can move from engagement in the slot 45 in the cylinder 14 into engagement in the said registering notches 37 and 38 with the result that the turn table 41 can now be freely turned for the operation of the latching bolt 11.

If it is desired to release the latching bolt 11 against the spring tension thereon within the casing 10, it is required that the rings 32 and 33 be held in a position or remain in a position to have the notches 37 register with the notch 38 in the ring 31 and the finger 44 accommodated within these notches and free from engagement in the slot 45 in the cylinder 14. In this event when the key 23 is inserted in the way 22 in the

barrel 15 the tumblers 24 within the barrel will be operated upon to free the said barrel for the turning thereof and by the turning of the same a limited distance the latch bolt 11 can be thrown to unlatching position against spring action within the casing 10 urging it to latching position.

The indicator or pointer arm 28 on the head 27 of the key 23 when thrown to an operative position for cooperation with the dial 16 will enable an operator of the key 23 to turn the barrel 15 and identify the setting of the rings 31, 32 and 33 according to the selected combination of the lock through observation of the numerals one to twelve and the degree marks 17 on the 15 said dial for the working of the lock.

The lock hereinbefore described is susceptible of being operated in three ways, for example, as a key operated spring latch or lock; a combination lock and as both the key operated spring and combination lock together as may be required by the user of such lock.

What is claimed is:

A lock of the kind described comprising a cylinder for stationary fitting in a part, a turn-

able barrel fitting said cylinder and having key released tumblers for locking the barrel with said cylinder, a cam ring fixed with the barrel and having an inset cam with respect to its outer periphery and providing a notch in said periphery, peripherally notched rings loosely fitted with the barrel at opposite sides of the cam ring and having variable lengthened annular channels next to said cam ring, means on the cam ring and active in the channels for changing the position of the notched rings for bringing the notches in the latter and said cam ring in alignment with each other, a turn table fitting the cylinder and swiveled with the barrel and having connection with a spring tensioned latch bolt for the throwing of the same counter to the spring tension thereof, and means movably fitted with the turn table for locking engagement with the cylinder and on release therefrom receivable in the notches when aligned with each other and moved by the 10 inset cam of the cam ring to locked position.
